UNITED STATES PATENT OFFICE

CHARLES SEAMAN, OF HOLLIS, NEW YORK

SHIRRING ATTACHMENT

Application filed December 24, 1927. Serial No. 242,508.

The present invention relates to sewing machine attachments, and particularly to such attachments designed for shirring or ruffling material being applied or stitched to other material.

Heretofore, it has been the practice generally to shirr or ruffle material by a blade or attachment operated in advance of the feeding means of a sewing machine, and such devices are usually limited in their operation and often require changes and alterations in the sewing machine.

The object of the present invention is to provide an attachment constructed and designed to deliver a ruffle strip or material to be shirred to the usual feeding means of a sewing machine in such a manner and under such conditions that said feeding means ruffles or shirrs the material and delivers other cloth or material in a manner that will permit the ruffled material to be stitched either to the folded edge of said cloth or to the body portion thereof.

A further object of the invention is to provide an attachment which can be readily applied to and removed from the standard type of sewing machine without any change or alteration in the machine.

Another object of the invention resides in the provision of means to regulate the position of the main presser foot with respect to the feeding means of the usual machine so as to control the degree of shirring or ruffling desired.

A further object of the invention is to provide an attachment having adjustable means to shift the ruffle material with respect to the needle of the sewing machine, so that the ruffle material may be stitched to the body material at any point between the edges of the former, thus permitting the widths of the heading of the ruffles to be varied.

A still further object of the invention is to provide an attachment having an auxiliary presser foot to overlie and engage the forward portion of the feeding means of a sewing machine in advance of the main presser foot thereof, and means for guiding ruffle material under said auxiliary presser foot,

the body material being fed over said auxiliary presser foot.

Another object of the invention resides in accessible means for readily raising said auxiliary presser foot out of engagement with the feeding teeth of the sewing machine, so that the material thereunder may be inserted or slipped out of place.

A further object of the invention resides in mounting said auxiliary presser foot so that it may be bodily shifted out of the plane of said feeding means of a sewing machine.

A still further object of the invention resides in said auxiliary presser foot having an edge folder mounted on its upper side, so that an edge of the body material may be folded prior to being presented under the needle.

Other objects and advantages of the invention will become apparent from the following description when taken in connection with the accompanying drawings, in which

Figure 1 is a side elevation of a sewing machine having the attachment applied thereto.

Figure 2 is a plan view taken substantially on line 2—2 of Figure 1 so as to illustrate the position the attachment assumes on the base plate of the machine.

Figure 3 is a perspective view of the attachment as generally shown in Figure 2.

Figure 4 is an end view of a sewing machine head equipped with the invention and looking substantially from the left hand side of Figure 1.

Figure 5 is a detailed view of the presser foot adjustment means.

Figure 6 illustrates the work done by the machine.

Figure 7 is an edge view of Figure 6.

Referring in detail to the drawings, 1 denotes the base plate upon which is mounted the usual sewing machine head 2, supporting a vertical reciprocating needle rod 3 actuated in any suitable manner from the pulley 4. It is understood, of course, that the needle bar 3 removably receives a needle 5. Through the eye of the needle extends a thread 6 drawn through tension devices 7 and 8 of conventional or desirable types. The machine also includes a work feeding mechanism or feed

dog 9 arranged under a vertical reciprocating main presser foot 10. The needle 5, the feeding mechanism 9 and the presser foot 10 are common to most all sewing machines. The 5 feeding means usually is in the form of rack or tooth bars positioned in slots 11 in the base plate and actuated by a suitable means from the machine whereby it is alternately projected through and lowered in the slots. When 10 projected it moves in one direction in the slots. All of this construction is usual in sewing machines and forms no part of this invention.

The present invention resides in an attachment A designed to be positioned in advance 15 of the presser foot 10 for guiding materials under the needle and main presser foot, so that one of the materials may be acted upon by the feeding means to be shirred thereby at the time it is being stitched to the other material.

This attachment mainly consists of a frame including a base plate 12 of any suitable design or construction but is here shown as being 20 an elongated strip of metal adapted to lie flat against the base 1 of the sewing machine and to be removably secured thereto by a screw or thumb nut 13. There is provided a downwardly extending lug 14 on the plate to extend through an opening in the base 1 of 25 the machine for cooperating with the fastening screw 13, so that the attachment may be properly positioned with respect to the needle 5, the feeding means 9 and the presser foot 10.

30 Laterally extending from the plate 12 is a rigid arm 15 upon which a spring finger 16 is horizontally pivoted. The finger 16 is preferably formed of resilient or spring metal pivoted intermediate its ends at 16a to 35 the arm 15 and has a rearwardly extending handle-forming end 18 designed to engage in a notch or recess 19 on the bar 20 laterally extending from the plate 12 and in advance of the arm 15. The other end of the finger 40 16 is so formed or constructed as to extend downwardly from the pivot point 16a and has a substantially flat end portion forming an auxiliary presser foot 17 to overlie and bear against the teeth *t* of the feeding mechanism 9 in advance of the needle 5. The extremity of the auxiliary presser foot 17 is notched as at 21 and through which notch the needle 5 extends during the stitching operation. The handle portion 18 of the 45 spring finger 16 also is formed to exert a spring tension downwardly upon the bar 20, so that the same will snap into the notch or recess 19 and be retained against accidental displacement, thus insuring the proper positioning of the notch 21 on the end of the 50 foot 17.

As shown in the drawings, it is preferred to have the surface of the presser foot 10, which coacts with the teeth *t* of the feeding mechanism to terminate at a point in advance

of the extremity of the auxiliary presser foot 17, as shown particularly in Figure 4.

It will be obvious, therefore, that, when the ruffle material R is passed between the foot 17 and the teeth *t* of the feeding mechanism and the body material B is passed under the main presser foot while overlying the auxiliary foot 17, the ruffle material will be kept in close contact with the teeth *t* and be fed at a greater speed to the needle 5 than 75 will the body material B, resulting in the ruffle material being shirred or puckered as it is being stitched to the body material. The degree of puckering or shirring can be regulated by reducing the pressure or clearance 80 of the under face of the main presser foot upon or with respect to the teeth *t*. This regulation may be accomplished in any suitable manner, but as one example, a stop bar 22 is secured to the upper end of the main 85 presser foot bar 10a, as at 40, and has a portion 41 which abuts an adjustable stop 23 threaded on a relatively fixed portion of the machine structure. Manifestly, the higher 90 the bottom face of the main presser foot 10 is maintained with respect to the teeth *t* the greater the shirring or puckering of the ruffle material R.

In order that the ruffle material may be fed to the needle in definite relation with respect 95 thereto, a flat guide loop 24 is provided through which the ruffle material passes, this guide having a supported arm 24a adjustably secured to the base plate 12 of the attachment by means of a thumb screw 25. As 100 can be clearly seen from the drawings, the guide 24 is adjustable across the path of the feeding movement of the ruffle material R, so that the material may be shifted transversely of said path in order that the needle 105 5 may penetrate the same at any point transversely thereof, as may be desired, whereby the width of the heading of the ruffle may be increased or diminished as can be observed 110 from Figure 6.

The auxiliary presser foot 17 has mounted thereon an edge folder 26 of the usual construction and arranged to normally align with the needle 5 and main presser foot 10. Thus, when it is desired to apply a ruffle to 115 edge of a body fabric, the said edge is passed through said folder 26 and is delivered to the needle 5 in a folded condition. The result of this operation can be observed from the ruffle R' in Figures 6 and 7, which is 120 stitched to the folded edge 27 of the body fabric B.

When it is desired to apply a ruffle, such as R'', see Figures 6 and 7, the body fabric is not passed through the folder 26, but over the same and the guide 24 is adjusted so as to give the ruffle the proper or desired heading. Thus, it is obvious that the present attachment permits the application of ruffles either to the edge of a body fabric or to points 130

between its edges without any change in or adjustment of the attachment except that which may be desired to obtain a proper heading for the ruffle by means of the guide 24.

5 In the operation of a machine having the attachment applied thereto, it may be desired to raise the auxiliary presser foot 17 out of engagement with the teeth of the feeding 10 mechanism, such as may be necessary when the thread breaks or it is desired to readjust the materials being worked upon. Various 15 means may be provided to attain this result. In the drawings I have illustrated one modification for attaining this result. The means comprises a lever 27 pivoted intermediate its 20 ends, as at 28, to the free end of the arm 15, and having at one end a bevel portion 29 adapted to engage the spring foot 17 at its 25 under face and raise the same against its spring tension when the handle 27 is moved in a direction of the arrow adjacent thereto, as shown in Figures 2 and 3. This will give sufficient clearance for any adjustment of the fabric that may be desired.

After a row of stitching has been made with the attachment and it is desired to remove the work from the machine, the handle 18 is raised out of the notch 19 and swung 30 about the pivot 16a to move the spring foot 17 laterally out of the position with respect to the feeding mechanism 9, the presser foot 10 and needle 5 and to either side thereof, as may be required or desired.

35 During the sewing operation with the present invention, the body cloth B may be handled or manipulated by the operator, but the ruffle strip is fed automatically from the source of supply, usually adjacent and below the machine. In order to facilitate this automatic feeding, the attachment is provided 40 with guide and tension devices for directing the movement of the ruffle material, which devices include as arm 30 having an angular 45 end portion 31 adjustably mounted on the plate 12 of the attachment for adjustment longitudinally of the machine. This arm 30 preferably extends obliquely with respect of the plate 12 and provided at its outer end 50 with an open loop 32. The ruffle material is first brought through the loop 32 from its source of supply and then through a guiding device 33 which diverts the direction of movement of the strip. This guiding device 55 consists of a bar 34 supported on the plate 12 of the attachment and extending in a plane substantially parallel with the path of movement of the material as it passes under the presser foot 10.

60 Associated with the bar 34 are the bars 35 and 36 extending at oblique angles with respect to the bar 34 and converging and meeting at the outer end thereof. It will thus be seen that the ruffle material R being led from the loop 32 may pass over the bar 35, under

the bar 34 and around the bar 36, so that the direction of movement of the ruffle material, after passing around the bar 36, will be parallel with the movement of the feeding means 9 of the sewing machine. The bar 36 70 is of a length sufficient to receive ruffle strips of varying widths and to permit the shifting of the same relative to the feeding means of the sewing machine by adjustment of the guide 24. Between the bar 36 and the guide 75 24 a further tension device is provided consisting of a plurality of spaced parallel reeds or bars 37 arranged transversely of the direction of movement of the ruffle material R and over and through which the said material is threaded or trained. These bars 37 have one end secured to the base plate 12 of the attachment and their other ends secured to a side piece or arm 38 secured to the bar 20.

80 From the above it will be observed that an attachment is provided for sewing machines so constructed as to cooperate with the usual feeding means of the sewing machine and cause the latter to shirr ruffles as they are being passed through the machine and stitched 85 to a body material.

85 It will also be observed that the present attachment is so constructed and designed that the shirred ruffles may be stitched to any point of the body material either to a folded 90 edge thereof or at a point between the edges of the body material without necessitating any change in the attachment or the removal of the same from the machine, the degree of shirring or ruffling being controlled by the 95 adjustment of the main presser foot with respect to the feeding means of the machine.

100 It is to be understood that, while I have shown for the purpose of illustration a selected embodiment of my invention, numerous changes in detail of construction, combination and arrangement of parts may be made without departing from the scope of the invention which is only intended to be limited by the appended claims.

110 What is claimed is:

115 1. The combination with a sewing machine having a single feeding dog, a presser foot and a needle, of an attachment removably secured on the machine comprising a spring finger adapted to cooperate with a portion of the feeding dog independently of the movement of the presser foot, means for guiding a ruffle strip between said feeding dog and finger, said finger being associated with said presser foot so as to permit other material to be fed over said finger and under said presser foot.

120 2. The combination with a sewing machine having a single feeding dog, a presser foot and a needle, means for vertically adjusting said presser foot to vary its effective relation with respect to the feeding dog, of an attachment removably secured on the machine comprising a spring finger normally coop-

- erating with the feeding dog in advance of the needle, means for guiding a ruffle strip between said feeding dog and finger, said finger being associated with said presser foot 5 so as to permit other material to be fed over said finger and under said presser foot.
3. The combination with a sewing machine having a single feeding dog, a presser foot and a needle, of an attachment removably secured on the machine comprising a spring finger normally cooperating with the feeding dog in advance of the needle, means for guiding a ruffle strip between said feeding dog and finger, said finger being associated with said 10 presser foot so as to permit other material to be fed over said finger and under said presser foot, and a folder on said finger adjacent said presser foot, whereby an edge of the body material may be folded in advance of the 15 needle.
4. The combination with a sewing machine having a single feeding dog, a presser foot and a needle, of an attachment removably secured on the machine comprising a spring finger adapted to cooperate with a portion of the feeding dog independently of the movement of the presser foot, means for delivering a ruffle strip between said feeding dog and finger, said finger being associated with said presser foot so as to permit other material to be fed over said finger and under said presser foot, and a guide through 20 which the ruffled material passes, said guide being adjustable transversely of the path of movement of said material.
5. The combination with a sewing machine having a single feeding dog, a presser foot and a needle, of an attachment removably secured on the machine comprising a spring finger adapted to cooperate with a portion of the feeding dog independently of the movement of the presser foot, means for guiding a ruffle strip between said feeding dog and finger, said finger being associated with said 25 presser foot so as to permit other material to be fed over said finger and under said presser foot, and means for raising said spring finger out of contact with said feeding dog.
6. The combination with a sewing machine having a single feeding dog, a presser foot and a needle, of an attachment removably secured on the machine comprising a spring finger adapted to cooperate with a portion of the feeding dog independently of the movement of the presser foot, means for guiding a ruffle strip between said feeding dog and finger, said finger being associated with said 30 presser foot so as to permit other material to be fed over said finger and under said presser foot, said spring finger being pivotally mounted and capable of being shifted laterally to one side of said feeding dog.
7. In a sewing machine, a needle, a main 35 presser foot and a single feeding dog under
- said main presser foot, an auxiliary presser foot normally in constant engagement with said feeding dog at a point in advance of the needle, said auxiliary presser foot being positioned to permit the material to be shirred to be fed thereunder to engage the feeding dog and the material to which the shirred material is to be secured fed thereover to pass under said needle and main presser foot. 70
8. In a sewing machine a needle, a main presser foot, and a single feeding dog under said needle and main presser foot, an auxiliary presser foot of resilient material positioned over said feeding dog at a point in advance of the needle, means for securing said auxiliary presser foot in position, said auxiliary presser foot being arranged to permit the material to be fed over and under the same to a point under said needle, said main presser foot being vertically adjustable in its effective positions 80 with respect to said feeding dog. 85
9. In a sewing machine a needle, a main presser foot and a single feeding dog under said needle and presser foot, an auxiliary presser foot of resilient material adapted to cooperate with a portion of the feeding dog independently of the movement of the presser foot, means for securing said auxiliary presser foot in position, said auxiliary presser foot being arranged to permit the material to be fed over and under the same to a point under said needle, and a pivoted hand lever arranged under said auxiliary presser foot adapted to raise the same out of engagement 90 with said feeding dog. 95
10. In a sewing machine a needle, a main presser foot and a single feeding dog under said needle and main presser foot, an auxiliary presser foot of resilient material positioned over said feeding dog at a point in advance 100 of the needle, means for securing said auxiliary presser foot in position, said auxiliary presser foot being arranged to permit materials to be fed over and under the same to a point under said needle, and adjustable means for varying at will the operable distance of the presser foot with respect to said feeding dog. 105
11. In a sewing machine a needle, a main presser foot, a single feeding dog under said needle and main presser foot, a normally stationary auxiliary presser foot of resilient material adapted to cooperate with a portion of the feeding dog independently of the movement of the presser foot, means for securing said auxiliary presser foot in position, said auxiliary presser foot being arranged to permit materials to be fed over and under the same to a point under said needle, and a guide in advance of said auxiliary presser foot through which the ruffle material passes, said guide being adjustable 110 transversely of the feeding dog to vary the position of the ruffle material with respect to the needle. 115
- 120
- 125
- 130

12. A shirring attachment for sewing machines comprising a frame attachable to a machine, a spring finger mounted on the frame forming an auxiliary presser foot to overlie a portion of a single feeding dog of the sewing machine in advance of the needle. 5
13. A shirring attachment for sewing machines comprising a frame attachable to a machine, a spring finger mounted on the frame forming an auxiliary presser foot to overlie a portion of a single feeding dog of the sewing machine in advance of the needle, and an edge folder mounted on said auxiliary presser foot. 10
14. A shirring attachment for sewing machines comprising a frame attachable to a machine, a spring finger mounted on the frame forming an auxiliary presser foot to overlie a portion of a single feeding dog of the sewing machine in advance of the needle, and means mounted on the frame to raise said auxiliary presser foot at will against its spring tension. 15
15. A shirring attachment for sewing machines comprising a frame attachable to a machine, a spring finger mounted on the frame forming an auxiliary presser foot to overlie a portion of a single feeding dog of the sewing machine in advance of the needle, said finger being laterally shiftable on said frame. 20
16. A shirring attachment for sewing machines comprising a frame attachable to a machine, a spring finger mounted on the frame forming an auxiliary presser foot to overlie a portion of a feeding means of the sewing machine, a handle member on said finger operable to shift said finger laterally to various positions, a lever pivoted on the frame and having one end underlie said finger and adapted to engage and shift vertically said finger against the spring tension thereof. 25
17. A shirring attachment for sewing machines comprising a supporting frame including a pair of parallel arms, a resilient member pivoted intermediate its ends to one of said arms and having one end extended across the other of said arms to frictionally engage the same, the other end of said member extending downwardly and formed with a substantially flat end portion to provide an auxiliary presser foot for a sewing machine. 30
18. A shirring attachment for sewing machines which includes a feeding dog comprising a supporting frame including a pair of parallel arms, a resilient member pivoted intermediate its ends to one of said arms and having one end extended across the other of said arms to frictionally engage the same, the other end of said member extending downwardly and formed with a substantially flat end portion to provide an auxiliary presser foot, said presser foot being positioned in engaging relationship with a portion of the feeding dog. 35
19. A shirring attachment for sewing machines comprising a supporting frame including a pair of parallel arms, a resilient member pivoted intermediate its ends to one of said arms and having one end extended across the other of said arms to frictionally engage the same, the other end of said member extending downwardly and formed with a substantially flat end portion to provide an auxiliary presser foot for a sewing machine, a guide positioned under said member and adjustable transversely of said frame. 40
20. A shirring attachment for sewing machines comprising a supporting frame including a pair of parallel arms, a resilient member pivoted intermediate its ends to one of said arms and having one end extended across the other of said arms to frictionally engage the same, the other end of said member extending downwardly and formed with a substantially flat end portion to provide an auxiliary presser foot for a sewing machine, and means mounted on the frame to raise said auxiliary presser foot at will against its spring tension. 45
21. A shirring attachment for sewing machines which includes a feeding dog comprising a supporting frame including a pair of parallel arms, a resilient member pivoted intermediate its ends to one of said arms and having one end extended across the other of said arms to frictionally engage the same, the other end of said member extending downwardly and formed with a substantially flat end portion to provide an auxiliary presser foot, said presser foot being positioned in engaging relationship with a portion of the feeding dog, a guide positioned under said member and adjustable transversely of said frame, and a tension device positioned in advance of said guide through which the material will pass. 50
22. A shirring attachment for sewing machines comprising a frame attachable to a machine, a spring finger mounted on the frame forming an auxiliary presser foot to overlie a portion of a single feeding dog of the sewing machine in advance of the needle, means on the frame to guide material under said presser foot, other means on the frame for initially guiding the material at substantially right angles with respect to said first guide, and a bar on the frame arranged in advance of said first guide and at an oblique angle with respect thereto, whereby the direction of movement of the material may be directed to said first guide. 55
23. A shirring attachment for sewing machines comprising a frame attachable to a machine, a spring finger mounted on the frame. 60

- frame forming an auxiliary presser foot to overlie a portion of a single feeding dog of the sewing machine in advance of the needle, means on the frame for guiding material 5 under said presser foot, other means on the frame for initially guiding the material at substantially right angles with respect to said first guide, and a bar on the frame arranged in advance of the first guide and at an oblique 10 angle with respect thereto, whereby the direction and movement of the material may be directed to said first guide, and a plurality of substantially parallel spaced reeds lying between said oblique bar and said first guide 15 through which said material may be threaded.
24. In a sewing machine arrangement designed to ruffle fabrics, the combination comprising a single feeding dog, a presser foot, a needle, a spring finger positioned proximate 20 one side of the needle and bearing against a portion of the feeding dog independently of the movement of the presser foot, whereby any fabric disposed between said spring finger and said feeding dog will be advanced 25 towards the needle, said presser foot being arranged in cooperative relationship proximate the other side of the needle so as to effect a differential feeding action on both sides of said needle, and means for adjusting the 30 position of said presser foot with respect to said feeding dog so as to obtain a selective differential feeding action on both sides of the needle. 90
25. In a sewing machine arrangement designed to ruffle fabrics, the combination comprising a single feeding dog, a presser foot, a needle, a finger positioned proximate one side of said needle and adapted to cooperate 35 with a portion of the feeding dog independently of the movement of the presser foot, whereby any fabric disposed between said finger and said dog will be advanced towards the needle, said feeding dog and said presser foot being arranged in cooperative relation- 40 ship proximate the other side of the needle so as to effect a differential feeding action on both sides of said needle. 105
26. In a sewing machine arrangement designed to ruffle fabrics, the combination comprising a feeding dog, a presser foot, a needle, a finger positioned proximate one side of said needle and adapted to cooperate with a portion of the feeding dog independently of the movement of the presser foot, whereby 50 55 any fabric disposed between said needle and said feeding dog will be advanced towards the needle, said feeding dog and said presser foot being arranged in cooperative relationship proximate the other side of the needle 60 so as to effect a differential feeding action on both sides of said needle, and means for adjusting the position of said presser foot to vary its effective relationship with respect to the feeding dog. 110
27. In a sewing machine arrangement de- 65

signed to ruffle fabrics, the combination comprising a single feeding dog, a presser foot, a needle, a spring finger positioned proximate one side of said needle and bearing against a portion of the feeding dog independently of the movement of the presser foot, whereby any fabric disposed between said spring finger and said feeding dog will be advanced towards the needle, said feeding dog and said presser foot being arranged in cooperative relationship proximate the other side of the needle so as to effect a differential feeding action on both sides of said needle. 70 75

In testimony whereof, I have affixed my signature to this specification. 80
